UNITED STATES PATENT OFFICE

DANIEL J. FINUCANE, OF BROOKLYN, NEW YORK

LEADER-PIPE STRAP

Application filed September 6, 1928. Serial No. 304,211.

This invention relates to straps or bands adapted for use in the attachment of water-conductor or leader-pipes to the walls of buildings and is in the nature of an improvement upon the invention disclosed in Letters Patent of the United States Number 1,676,485, granted to me on July 10, 1928.

Leader-pipes, in accordance with a practice widely followed, are supported by placing the sides thereof between the arms of a U-shaped staple or bracket having a central prong adapted to be driven into the wall. A wire attached to the outer ends of the staple arms and spanning the front surface of the leader-pipe holds the latter in its position in the staple. In order to conceal the staple and wire, a metal band which embraces the front and sides of the leader-pipe is then placed over the fastening with end portions 20 of the bands folded outward to lie flat against the wall of the building. In my patent referred to above, disclosure is made of a band of the character indicated and suitable for this purpose, said band comprising embossed 25 ornamental ends and successive body portions having reinforcements embossed therein, the body portions being separated from one another and from the ornamental ends by bending zones adapting the strap to be 30 bent into conformity with the leader-pipe and with the wall of the building. These features are also utilized in the illustrative embodiment of the present invention.

It is an object of the present invention to 35 provide a strap capable of effecting a more complete concealment of the leader-pipe supporting staple and wire than heretofore, and yet adaptable to installations varying through a considerable range.

It is a further object to provide a construction 40 in which the end and body portions are more rigid than heretofore and in which the bends between the side body portions and the ends of the strap are adapted to be more 45 sharply defined so that the body portions and ends may not merge through a curved portion of large radius but be each in its separate plane. Because of these features the strap is adapted to grip the pipe more securely 50 than the prior construction and to

serve more effectively as a support for the pipe, whether used in conjunction with the staple or other spacer or used separately for gripping the pipe directly against the wall.

Leader-pipes are generally standardized 55 so that a line of supporting straps suitable for all usual installations may be confined to a small number of standard sizes so far as the requirements imposed by variation in leader-pipe dimensions are concerned.

It is common practice, however, for architects to specify that the leader-pipe be supported at a distance outward from the wall of the building, such installation being in some cases necessitated by irregularities in 60 the face of the building and in other cases considered desirable for other reasons. Such spacing requirements on different jobs vary considerably. It is, accordingly, an important aim of the present invention to provide 65 a strap which is adaptable to all usual spacing requirements and which therefore can be made in one standard size for a given size of leader-pipe.

It is a further object of the invention to 70 provide flanges along the edges of the strap in order that a housing or boxing may be formed when the strap is bent into conformity with the leader-pipe to completely conceal the staple and wire. Such flanges are 75 designed to extend continuously throughout the length of the strap except at the particular points at which bending is desired, and therefore cause the bends to be sharply defined and prevent deformation elsewhere than 80 at the lines of bending.

Other features of the invention relate to the cutting of these flanges in the bending zones between the side and end portions, and to the offsetting of adjacent ends of the 85 flange sections between the front and side body portions so that the flanges will be situated in such relation to one another that they will not interfere with the desired bending of the strap.

Other objects and advantages will herein-after appear.

In the drawings forming part of this specification,

Figure 1 is a plan view partly in section and 101

partly broken away, showing a leader-pipe supported on a wall and surrounded by a strap embodying features of the invention;

5 Figure 2 is a view similar to Figure 1 showing an identical strap applied to another installation in which the spacing requirements are different from those of Figure 1;

10 Figure 3 is a fragmentary vertical sectional view through a leader-pipe and the supporting strap of Figures 1 and 2;

15 Figure 4 is an edge view of a strap of the kind disclosed in Figure 1 showing the strap in the form in which it is received on the job; and

20 Figure 5 is a plan view of the strap shown in Figure 4.

25 In Figure 1 a leader-pipe 1 is shown supported from a building wall 2 by means of a U-shaped bracket 3 having a central driving prong 4 penetrating the wall. The leader-pipe is bound to the bracket by a wire 5 passed around the front face of the leader-pipe and wrapped at its ends around hooked ends 6 at the outer ends of arms 7 of the bracket 3. It will be observed that the bracket 3 does not have its shank 4 driven completely into the wall but that it is spaced outward a short distance from the wall. The leader-pipe itself may be regarded as one of standard size.

30 The bracket 3 and wire 5 are concealed and substantially housed by a facing strap 8. Such strap comprises flanged end portions 9 having ornamental embossments 10 formed therein. Such strap further comprises a central body portion 11 and side body portions 12 and 13 which body portions have reinforcing embossments 14, 15, and 16, formed in their respective faces. The central body portion 11 is provided with side flanges 17 and the side body portions 12 and 13 are provided with side flanges 18 and 19 respectively. These flanges are adapted to form upper and lower housing walls and to engage the front and side faces of the leader-pipe when the strap is bent into conformity with the leader-pipe. Intermediate the central body portion 11 and the side body portions 12 and 13, the reinforcing embossments are omitted so that flexible bending zones are provided to facilitate application of the strap to the leader-pipe. At the bending zone 20 the flanges 17 are separated from the flanges 18 and at the bending zone 21 the flanges 17 are separated from the flanges 19. In order that the flanges shall not interfere with bending of the strap the inner ends of flanges 18 and 19 are formed with offsets 22 and 23 to disalign them with respect to the flanges 17.

35 60 It will be seen from a comparison of Figures 1 and 2 that in effecting different installations, it will be necessary to bend outward the ornamental end portions of the strap at different points. In order to enable this to be done, provision is made between

the body portion 12 and one end portion 9 of an unembossed bending portion 24 and between body portion 13 and the opposite end portion 9 of an unembossed bending portion 25. These bending portions 24 and 25 are made of substantial length sufficient to accommodate all of the variations ordinarily encountered in the spacing of leader-pipes outward from walls. As seen in Figure 1, for example, the leader-pipe is located fairly close to the wall and the strap is bent in portions of the bending zones 24 and 25 closely adjacent to the body portions 12 and 13. In Figure 2 on the other hand, the leader-pipe is spaced a substantial distance outward from the wall and the bending is effected in the bending zones 24 and 25, at points closely adjacent to the ornamental end portions 9.

35 40 45 In order to effect this bending, the workman determines by measurement the locations in the bending zones at which the bending is required by the particular leader-pipe installation on which he is working and then cuts through the flanges 18 and 19 in the appropriate portions of the bending zone for permitting the bends to be formed at the desired points. The strap is then bent into the shape shown in Figure 1 or 2 and is either soldered to the leader-pipe or secured in place by nails 26 driven into the wall of the building. If desired, it may be both soldered to the leader-pipe and nailed to the wall, to assist in supporting the leader pipe in place.

45 50 55 It will be seen that the flanges 18 and 19 should preferably be cut in order to permit bending in the bending zones 24 and 25 and that when so cut the bending is confined in each zone to a line joining the cuts. The bends will, therefore, be sharply defined so that the production of a neat, attractive, workmanlike job will result as a matter of course.

60 65 70 75 While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

75 I claim:

1. A leader-pipe strap comprising body portions adapted to partially surround a leader-pipe, end portions adapted to lie against the face of a building and bending portions of substantial length connecting the end portions with the body portions, said bending portions being provided with longitudinally extending flanges adapted to be cut through at any determined bending line or zone and to confine bending substantially to such line or zone.

2. A facing strap for leader-pipe supports comprising body portions connected to one

another through bending portions, longitudinal flanges on the body portions to prevent bending, said flanges being interrupted or rendered discontinuous by separation in the bending portions, the adjacent ends of the flange sections being disaligned to avoid interference with bending.

5 3. A facing strap for leader-pipe supports comprising body portions connected to one another through bending portions, longitudinal flanges on the body portions to prevent bending, said flanges being interrupted or rendered discontinuous by separation in the bending portions, the ends of certain of the flange sections being offset to disalign them with respect to the ends of adjacent flange sections.

10 4. A facing strap for leader-pipe supports, comprising body portions adapted to partially surround a leader-pipe, end portions adapted to lie against the face of a building, bending portions of substantial length connecting the end portions with the body portions, and flanges at opposite ends of the strap each extending continuously along an end portion, a bending portion, and an adjacent body portion, said flanges adapted to be cut through to provide for bending in the bending portions, but serving to prevent bending except in the line or zone determined by such cutting.

15 In testimony whereof I have affixed my signature to this specification.

20 DANIEL J. FINUCANE.
